LAMP FOCUSING SIGHT

Wilbur T. Harding, Dayton, Ohio

Application August 27, 1934, Serial No. 741,718

6 Claims. (Cl. 176—16)

(Granted under the act of March 3, 1883, as
amended April 30, 1928; 370 O. G. 757)

The invention described herein may be manufactured and used by or for the Government for governmental purposes, without the payment to me of any royalty thereon.

5 This invention relates to a lamp focusing sight for use in locating or focusing a lamp filament in a projector.

The object of the invention is to provide a positive method of locating center of incandescent 10 lamp filament for focusing purposes by which it is possible to focus the filament center more accurately than heretofore.

To this end the invention consists of a fixed sight constructed as part of, or as an attachment to, the filament support of an incandescent 15 lamp so that when viewed from the side the end of the sight, being perpendicular to the center of the filament, may be used to focus the lamp filament.

20 Other objects and advantages of the invention will be apparent from the following detailed description of a specific embodiment thereof, read in connection with the accompanying drawing, whereas:

25 Figure 1 is a horizontal section of an airdome landing field floodlight unit embodying the invention.

Figure 2 is an elevation, with part of the lamp housing broken away to more clearly show the 30 lamp installation and focusing.

Figure 3 is an enlarged detail view of a selected lamp filament as modified to incorporate the invention therein.

Figure 4 is a section on line 4—4 of Figure 3, 35 and

Figure 5 is a view illustrating an alternate form of the invention.

For convenience of disclosure, the invention is shown and described as embodied in a 4-coil 40 monoplane filament lamp to which it is especially applicable but not limited. Referring more particularly to Figures 3 and 5, it will be noted that the 4-coil filament 1 is attached at its ends 3 to the lead-in wires 5 and is supported between

45 the lead-in wires with its coils vertical by a filament support 7 consisting usually of a thin wire having its lower end hooked around the filament as shown at 9, Figure 5, and its upper end fixed to an insulator 11 connected to and bridging between

50 the space between the upper ends of the lead-in wires.

The lamp focusing sight constituting the subject matter of the present invention may be constructed as an integral part of the filament support 55 7, as shown in Figure 4, or it may be sepa-

rate therefrom, as in Figure 5. In the first instance, the support 7 is prolonged as at 13, beyond the filament hook 9 to extend rearwardly and downwardly of the filament to a point coinciding with the filament center, the end 15 of the prolongation or sight 13 being perpendicular to the center of the filament so that when viewed from the side it may be used to focus the lamp filament. When applied to the lamp as an attachment, as in Figure 5, the fixed sight consists 10 merely of a sight wire 13a fixed at its upper end to, and depending from, the insulator 11 directly back of the filament supporting wire 7 with its lower end 13a perpendicular to the center of the filament as shown.

15 A lamp of the 4-coil monoplane filament type is frequently used as a light source in a parabolic reflector floodlight, for illuminating an airdome landing field. When so used, the plane of the lamp filament is placed parallel to the directrix 20 plane of the parabola. Such floodlights usually have peep sights and crosses for focusing the lamp. An airdome landing field floodlight unit is conventionally shown in Figures 1 and 2, and consists of a lamp housing 17 equipped with a lens 25 19 and a reflector 21 between which is located the lamp 23; the latter being adjustable in the lamp socket 25 to position its illuminating center, or filament center, at a desired point or focus. The lamp housing is provided with suitable 30 means, such as peep holes 27—27 and 29—29, defining lines of sight 31 intersecting within the casing and at the desired or focal point for the filament center. Since commercial filament 35 lamps have no means definitely marking the filament center, the lamp focusing operation is subject to errors in judging the center location, since the center location when viewed at an angle, usually along lines of sight shown at 31, cannot be readily ascertained. With the fixed 40 sight arrangement of the invention, however, the filament center is definitely and positively marked and makes it possible to locate the filament center more accurately at the focal point.

45 It will be understood that while the invention has been specifically shown and described as applied to a 4-coil monoplane filament lamp, it is equally applicable to other types of filament lamps.

Having thus described the invention, what is 50 claimed as new is:—

55 1. A filament lamp having, in combination, a lamp filament; a filament support; and a sighting element pointing to and positively indicating the center of the filament for lamp focusing purposes.

2. A filament lamp having, in combination, a lamp filament: lead-in wires for same: an insulator between the lead-in wires and above the filament: and a fixed sight depending from the insulator to a point in line with the center of the filament.
3. A filament lamp having, in combination, a lamp filament: lead-in wires for the same: an insulator between the lead-in wires and above the filament: and a fixed sight depending from the said insulator to a point in line with the center of the filament and having its sighting end, when viewed from the side, perpendicular to the center of the filament for lamp focusing purposes.
4. A filament lamp having, in combination, a lamp filament and a filament support having a sight forming portion positively indicating the center of the filament for lamp focusing purposes.
5. A filament lamp having, in combination, a filament: lead-in wires for the same: an insulat-

ing bridge between the lead-in wires and above the filament: a filament support fixed to and depending from said insulating bridge and in supporting connection with the filament, said filament support being prolonged beyond its connection with the filament to a point in line with the center of the filament to provide a fixed sight the end of which, when viewed from the side, is perpendicular to the filament center.

6. A filament lamp having, in combination, a filament: lead-in wires for the same: an insulator between the lead-in wires and above the filament: a filament support depending from the insulator and engaging the filament: and a sight fixed to and depending from the insulator in a plane parallel to the plane of the filament and having its lower or sight end in line with the center of the filament.

WILBUR T. HARDING. 20
